UNITED STATES PATENT OFFICE.

ROBERT CUMMING ANNAND, OF SOUTH SHIELDS, ENGLAND, ASSIGNOR TO
ROBERT HOE, OF NEW YORK, N. Y.

WEB PRINTING, ASSOCIATING, AND FOLDING MACHINE.

SPECIFICATION forming part of Letters Patent No. 734,112, dated July 21, 1903.

Application filed December 10, 1897. Serial No. 661,349. (No model.)

To all whom it may concern:

Be it known that I, ROBERT CUMMING ANNAND, of South Shields, England, have invented certain new and useful Improvements 5 in Web Printing, Associating, and Folding Machines, (part of which has been patented in Great Britain, No. 10,084, bearing date May 12, 1896,) of which the following is a specification.

10 My invention relates to web printing, associating, and folding machines; and its chief object is to provide a quadruple web-machine of improved construction in which the different printing mechanisms are arranged 15 in a handy and accessible manner, while at the same time the space occupied by the printing-machine and the associating, cutting, folding, and delivery mechanisms is less than that occupied by quadruple web-presses 20 as hitherto constructed.

The invention consists in arrangements and combinations of web printing, associating, and folding mechanisms and certain specific features of construction in blanket-cylinders 25 and paper-brakes, all as fully described and claimed hereinafter.

In the accompanying drawings, Figure 1 is a general view, in side elevation, of a quadruple web-printing machine in which my improvements are embodied. Fig. 2 is a side view of the associating mechanism with the switches in position for leading two of the webs to one folder and the other two webs to the other folder. Fig. 3 is a similar view, but 30 with the switches in position for leading all four webs to the folder which is at the left-hand side of the figure. Fig. 4 is a similar view, but with the switches in position for leading all four webs to the folder which 35 is at the right-hand of the figure. Fig. 5 illustrates one of the reels of paper in end view and the novel construction of brake. Fig. 6 illustrates the same parts in front view. Fig. 7 is a sectional view illustrating means 40 for connecting any of the presses to and from the driving mechanism. Fig. 8 is a face view illustrating the same means. Fig. 9 is a detail view of part of the device illustrated in Figs. 7 and 8. Fig. 1 is drawn to a smaller 45 scale than the other figures.

Stated broadly and as will be seen on ref-

erence to Fig. 1, the combined press consists of two lower and two upper printing mechanisms, one of the lower mechanisms being placed at each end of the combined machine 55 in a more or less upright position, while the other two printing mechanisms are arranged in a position slightly inclined from the horizontal, their inner portions being higher than their outer portions and with the framework 60 that carries them resting upon the top of the framework of the lower mechanisms. The printing-cylinders of all the four mechanisms are parallel to one another. By arranging the printing mechanisms in this manner I provide 65 space between the two end printing mechanisms and below the upper two for the web associating, cutting, folding, and delivery mechanisms, and the webs after they are printed have a comparatively short distance to travel 70 before reaching the folders. In my arrangement there are no cutting-cylinders in the printing mechanisms, and the webs are brought to the folders uncut and are folded longitudinally while still uncut, and the cutting 75 is effected after the webs have been longitudinally folded. This is a great advantage, as it saves time in feeding in fresh webs, saves paper when breakages occur, and there is no difficulty in keeping the register and 80 cutting right.

Referring now to the drawings, and more particularly to Fig. 1, P' and P² represent, respectively, the two lower printing-presses, and P³ and P⁴ the two upper presses. 85

A' A² A³ A⁴ are respectively the inking mechanisms, and B' B² B³ B⁴ the ink-fountains, of the four presses. These parts are of the usual kind and require no further description. Only a few of the composition rollers 90 are shown. Their arrangement can be varied as desired. They are usually arranged to suit the class of printing produced by the press.

R', R², R³, and R⁴ are the web-reels appertaining, respectively, to the four presses, and W' W² W³ W⁴ are the four webs of paper carried by and delivered from these reels. 95

C' C² C³ C⁴ are the stereotype-cylinders for printing the first side of the respective webs, 100 and D' D² D³ D⁴ are the corresponding blanket-cylinders.

$F' F^2 F^3 F^4$ are the stereotype-cylinders for printing the second side of the respective webs, and $E' E^2 E^3 E^4$ are the corresponding blanket-cylinders.

5 It will be seen that in the case of each of the two lower presses $P' P^2$ the inking mechanism $A' A^2$ is placed at the bottom, with the fountains $B' B^2$ outside. The first stereotype-cylinder $C' C^2$ is placed above the large ink-cylinder, and the corresponding blanket-cylinder $D' D^2$ is in the same horizontal plane. The blanket-cylinders $E' E^2$ and stereotype-cylinders $F' F^2$ for printing the second side of the web are arranged almost vertically 15 above the first blanket-cylinder, the second inking mechanism being arranged horizontally on the outside of the machine. By this arrangement the stereotype-cylinders $C' C^2 F' F^2$ lie with their upper sides fully exposed, 20 which admits of the stereoplates being put on and removed with great facility. In the case of each of the two upper presses the two stereotype-cylinders and the two blanket-cylinders are arranged in a straight line somewhat 25 inclined from the horizontal. It will be noticed that in these presses also the stereotype-cylinders $C^3 C^4 F^3 F^4$ lie with their upper sides fully exposed.

After the four webs $W' W^2 W^3 W^4$ are printed they pass the "registering-rollers" $H' H^2 H^3 H^4$ and thence by the pathways of moving tapes to the associating and folding mechanism, which is hereinafter described. It will be seen that the reels $R' R^2 R^3 R^4$ are 30 carried at the outside of the machine and that after all the webs have been printed they leave their respective presses on the inside. They are thus in close proximity to the folding mechanism, and therefore only comparatively 35 short lengths of the webs lie between the printing mechanisms and the folding mechanism. This is of great service in saving strain on the paper and in getting the register and cutting right.

45 I will now describe the associating mechanism for dealing with the webs after they have been printed and passing them on to the longitudinal folding device. This folding device may be a single longitudinal folder; 50 but preferably it consists, as in the arrangement shown, of two back-to-back longitudinal folders K' and K^2 , Figs. 1, 2, 3, and 4, which may be of any suitable form for folding the webs when on the run.

55 1 and 2 represent the under runs of tapes for bringing the two webs $W' W^2$, respectively, from the two lower printing-presses. The tapes 1 pass around, respectively, the rollers 8 and 14 and the tapes 2 around the rollers 9 and 15.

60 3 and 4 are the upper runs of tapes for the same webs. They return around rollers 16 and 17, respectively. Sets of tapes pass, as shown, around the rollers 11 and 12 and down 65 the face of the fold-formers $K' K^2$ to the pulleys 24 and 25. In order to draw up any slack on the webs, they are slightly nipped

between the tapes passing around the rollers 8 and 14 and the roller 11 and again between the tapes passing around 11 and 24 and the roller 14. Lower runs of tapes for each of the upper webs $W^3 W^4$ pass around the rollers 10, 19, and 20, and upper runs of tapes pass around the rollers 13 and 18. The rollers 8, 9, 10, 11, 12, and 13 are all driven by gearing 75 from the printing-machines, as will be well understood, and their surface speeds should be somewhat faster than the rate of travel of the webs. This insures that the webs are kept tight and that the register and cutting 80 are right.

L is a set of lower switches movable to the right and left on a horizontal axis L' .

M represents one of two or more parallel switch-bars free to slide on a fixed horizontal 85 rod M' , which is itself suspended from a bracket M^2 . The switch-bars M and rod M' are omitted in Fig. 1. The lower ends of the switch-bars M are split or open, so as to go over the upper edges of the switches L, as 90 seen in Fig. 2, and thus form an unobstructed pathway for the webs. When it is desired to run the lower web W' and the upper web W^3 to the folder K' and the other two webs W^2 and W^4 to the folder K^2 , the switches 95 L and M are placed as shown in Fig. 2. When it is desired to run all the webs to the folder K' , the switches M are slid along the rod M' to the ends of same against the sides of the framework. This puts them clear of 100 the webs, which are less wide than the framework. The switches L are moved to the position seen in Fig. 3 and also in Fig. 1. When it is desired to run all the webs to the folder K^2 , the switches L are moved to the position seen in Fig. 4.

The longitudinal folders $K' K^2$ are of the well-known form, consisting of a V-shaped internal guide or fold-former working in conjunction with external folding or drawing 110 rollers S S, which fold the paper when on the run. T T are transverse cutting and folding cylinders which sever the webs into sheets and give them one or more transverse folds, after which they are carried to the delivery 115 mechanism, which may be of any suitable form. $T' T'$ represent the gear-wheels by which the rollers S S and T T are driven. These wheels derive their motion from the shaft 36 through the intermediation of the 120 wheels X X. The cylinders S S and T T are carried in bearings forming part of the side frames at Z Z. There is also a central strut Z', (or there might be two central struts,) which carries in bearings the inner ends of the cylinders S S and T T. It is advantageous to have two separate and independent transverse cutting and folding mechanisms, as just described, for receiving longitudinally-folded webs or sets of associated webs from the two 125 folders $K' K^2$ instead of having one such mechanism the cylinders of which are sufficiently long to deal with longitudinally-folded webs from both or either of the folders $K' K^2$.

When there are, as described, two separate and independent mechanisms and one of them breaks down, the longitudinally-folded webs can be switched by the mechanism already described to the other folder.

The combined quadruple machine is shown as driven by two driving-shafts 26 26, which may receive their motion from any suitable prime mover—such, for example, as a steam or electric motor. The driving-shafts 26 26 carry toothed wheels 27 27, gearing with wheels 28 28 on the shafts of the blanket-cylinders E' E². The wheels 28 28 gear with wheels 29 29 on the shafts of the blanket-cylinders D' D². Motion is also transmitted from the wheels 27 27 to wheels 30 30 on the shafts of the blanket-cylinders D³ D⁴ by the intermediate gear-wheels 31 and 32 and from the wheels 30 30 to wheels 33 33 on the shafts of the blanket-cylinders E³ E⁴. On the shaft of each of the blanket-cylinders D' and D² is keyed a bevel-wheel 34, meshing with a bevel-wheel 35 on the respective ends of a horizontal shaft 36, which connects the two lower printing mechanisms. This shaft 36 is in two parts, with a releasable coupling of any suitable kind at 37. The two lower printing mechanisms can thus be worked together from either of the driving-shafts 26, or separately, as desired. The toothed wheels 30 30 on the shafts of the blanket-cylinders D³ D⁴ are mounted loosely on the said shafts, but can be connected therewith at will by means of any suitable arrangement—such, for example, as that shown in Figs. 7, 8, and 9, so that either of the two upper printing mechanisms may be driven or not, as may be required.

Referring to Figs. 7, 8, and 9, 30 is the toothed wheel, mounted loosely on the shaft of the blanket-cylinder D³, (or D⁴), and 32 is the wheel from which the wheel 30 receives its motion. a is a disk keyed on shaft of said blanket-cylinder. f is a bolt or plunger working in a hole in said disk, and h is a corresponding hole in the wheel 30. g is a spring, which may be either a flat spring, as shown, or of other suitable form tending to push the bolt f into the hole h. On the side of the bolt-head is a projection or pin k, working up against a snail or cam i, attached to the outside of the disk a. When it is required to disconnect the wheel 30 from the shaft of the cylinder D³, the bolt f is moved around by means of a key, and the projection k, by working against the snail i, withdraws the bolt from the hole h, as seen in Fig. 7. At the high part of the snail there is a depression or groove l, Fig. 9, into which the pin k drops to hold the bolt from turning backward. When it is required to connect the wheel 30 with the shaft, the bolt f is turned in the reverse direction and the spring g forces it into the hole h. The means just described for connecting and disconnecting the driving mechanism to and from the printing mechanism can be applied to any double, triple,

or multiple web-printing machine, as will be readily understood.

I will now describe the novel construction of brake for controlling the reels of paper. This brake is seen applied to all the four reels in Fig. 1 and is illustrated on a larger scale in Figs. 5 and 6. The brake is intended to steady the roll of paper and is applied to the surface of the paper itself. It gives a uniform tension not only when the roll is full size, but also while the roll gradually diminishes in diameter, and when the brake-pressure is once adjusted it is practically automatic. m is the brake shoe or band. It consists of a band of flexible material, such as leather, bearing against the roll of paper, as shown, and stretched tight. One end of the brake-band m is attached to a hook n on an arm o, and the band is tightened by means of a screw-hook p at the other end screwing into a nut q on the outer end of the arm o. The arm o is pivoted at its inner end on a horizontal rod r, fixed to the framework of the machine. On the rod r is a spring s, one end of which is attached to the arm o and the other end to the boss of a hand device, preferably a handle t, as shown, so that the spring has always a tendency to cause the arm o to move in the direction which will press the band m against the roll of paper. On the side of the handle t is a pawl u, which engages with a ratchet-wheel v on the rod r. By means of the handle t the spring s can be wound up to give any desired brake-pressure upon the paper-roll, and the pawl u retains the handle in the position to which it is moved.

What I claim, and desire to secure by Letters Patent, is—

1. In a quadruple web printing, associating and folding machine, two lower web-printing mechanisms arranged end to end on one level in one vertical plane and situated respectively at the opposite ends of the combined machine in an approximately vertical position with a space between them and with their printing-cylinders parallel to each other, two upper web-printing mechanisms situated respectively above the two lower web-printing mechanisms and arranged end to end on one level in the same aforesaid vertical plane, with their printing-cylinders parallel to each other and to the printing-cylinders of the two lower printing mechanisms, and with their framework resting directly upon the top of the framework of the two lower web-printing mechanisms, each of said upper web-printing mechanisms being in an approximately straight and inclined line with the inner end slightly higher, means for conveying the uncut printed webs from the respective printing mechanisms to folding mechanism and web-folding mechanism in the space between said lower web-printing mechanisms and below said upper web-printing mechanisms, substantially as set forth.

2. In a web printing, associating and folding machine, the combination of two lower

21. web-printing mechanisms arranged end to end on one level in one vertical plane with a space between them and with their printing-cylinders parallel to each other, two upper 5 web-printing mechanisms arranged end to end on one level in the same aforesaid vertical plane, with their printing-cylinders parallel to each other and to the printing-cylinders of the two lower web-printing mechanisms 10 and with their framework resting directly upon the top of the framework of the two lower web-printing mechanisms, a double back-to-back longitudinal web-folding mechanism in the space between the lower web-printing mechanisms and below the upper web-printing mechanisms, comparatively short pathways of tapes conducting the respective printed webs uncut to said web-folding mechanism, and movable switches where- 15 20 by the webs may either be all directed to the one side of the folding mechanism or to the other side of same, or two webs may be directed to the one side and two webs to the other side of said web-folding mechanism, 25 substantially as set forth.
3. In a quadruple web printing, associating and folding machine, having two lower web-printing mechanisms and two upper web-printing mechanisms, all disposed as hereinbefore specified the combination in the space 30 between the lower web-printing mechanisms and under the upper web-printing mechanisms of web-associating and double back-to-back longitudinal web-folding mechanism, 35 and two separate and independent transverse cutting and folding mechanisms for cutting the printed webs after these have been associated together and longitudinally folded, and whereby according to requirement said trans- 40 45 50 55 60 65 70 75 7c
- verse cutting and folding mechanisms can either be run together or either of them can be run while the other is stationary, substantially as set forth.
4. In a web-printing machine having more than one printing mechanism, a gear-wheel mounted loosely on the shaft of a blanket-cylinder and formed with a hole, a disk fixed on said shaft a snail or cam attached to the outside of said disk and formed with a depression or groove in its high part, a bolt working in a hole in said disk and adapted to be rotated by hand by means of a key, and formed with a projection working against said snail or cam tending to disconnect said disk from said blanket-cylinder, and a spring tend- 55 60 65 70 75 7c
- ing to push said bolt into the hole in the aforesaid gear-wheel, to connect said disk to said blanket-cylinder, substantially as and for the purpose set forth.
5. In a web-printing machine the flexible brake-shoe *m* in contact with the surface of the paper on the reel, the arm *o* pivoted to the framing and carrying said brake-shoe, a screwed part *p* for tautening the brake-shoe to any required degree, a coiled spring *s* tending to force said arm and said brake-shoe toward said paper, and a pawl-and-ratchet wheel for winding up the said spring and retaining it in the wound position, substantially as set forth.
- In witness whereof I have hereunto signed my name in the presence of two subscribing witnesses.
- ROBERT CUMMING ANNAND.
- Witnesses:
- JOHN C. NEWBURN,
GEORGE C. BACON.
